Inventor:
Royce L. Beers

UNITED STATES PATENT OFFICE.

ROYCE L. BEERS, OF DETROIT, MICHIGAN, ASSIGNOR, BY MESNE ASSIGNMENTS, TO RILEY STOKER CORPORATION, OF WORCESTER, MASSACHUSETTS, A CORPORATION OF MASSACHUSETTS.

SIDE TUYÈRE STRUCTURE.

Original application filed January 14, 1921, Serial No. 437,238. Divided and this application filed August 11, 1923, Serial No. 656,977. Renewed December 3, 1926.

My invention relates to side tuyère structures for arrangement between the margin of the retort structure and the contiguous side wall of the furnace for supplying air to the combustion space and protecting the furnace side wall against clinker adhesion through the zone of detrimental clinker formation. A general object of my invention is to provide a tuyère structure of the character stated which will be of narrow or "plate" construction, which will be simple, easily manufactured, inexpensive to install or to replace, and of advantageous construction, giving great resistivity to destruction by heat, capability to maintain such relative cool surface condition as will minimize clinkering, and other advantages.

To these ends my invention consists in the features of construction and arrangement hereinafter set forth, reference being had to the accompanying drawing wherein Fig. 1 is a side elevation of a plate tuyère constructed and arranged in accordance with my invention, fragments only of a known type of retort structure being shown in connection therewith; Fig. 2 front edge view of the tuyère structure, and Fig. 3 is a rear edge view thereof.

In the drawing 10 indicates fragmentarily the margin of the retort, of a multiple-retort rear-dumping stoker of known design, such for example, as the "Jones A-C" stoker, and 11 indicates the side wall of the furnace from which the margin of the extreme rotort of such a stoker is spaced, in substantial parallelism with the furnace side wall. 12 indicates in general the plate-tuyère structure which is adapted for interposition between the retort-margin and the side wall to extend up the latter to a height at or above the uppermost level of expectable detrimental clinker formation. In the specific construction shown such tuyère structure spans directly from the upper edge of the retort to the side wall, finding bearing against both of these parts. Such plate tuyère structure is shaped, in side elevation or face view, to provide a front edge portion 13 rising to a considerable height above the retort margin and preferably merging into the slope of the inner surface of said retort, a top-edge portion 14 extending laterally and upwardly, preferably at a more abrupt angle to the side

wall, for contact at its uppermost point with the side wall, and a rear edge 15 vertically disposed to rest against the side wall. The body-web 17 has the remainder of its rear edge 16 shaped to extend from the bottom of the portion 15 to a point in rear of and below the bottom of the portion 13, so that on the bottom of the structure a point 16' is formed to fall behind the margin of the retort and prevent displacement of the lower edge of the structure toward the interior of the retort. A lug 16'' may be suitably provided on the rear of the body-web apertured for receiving a suitable tie-rod.

A shallow flange 18 extends solidly along the top and wall-contacting sides of the plate, while the flange 19 follows its forward side (facing the retort) these flanges being preferably quite thin, and of uniform depth or projection from the body-web. Preferably such a flange is provided on one side only of the body-web.

The flange 19 may be interrupted by a lower group of tuyère notches 20, near the bottom of the structure, and an upper tuyère notch 21 is preferably provided to give an air escape opening close to the upper edge 14 of the plate. Preferably lugs 22 integral with the flange 19 extend rearwardly along the plate as lips aligning with the bottoms of the several tuyère openings. It will be understood that these tuyère plates will be placed side by side as assemblies consistent with the length of the retort.

In the operation of an underfeed stoker of the character described, an area of very active combustion will exist just above the level of the retort-margins, where air is supplied through tuyères practically corresponding in position with the lower tuyères 20, and at the furnace side wall clinker adhesion is apt to occur through a zone extending materially above the level of the retort margins. With respect to the structure illustrated, it will be seen that each body-web is adequately air-cooled by the constant passage of air from the windbox below the tuyère structure through the openings 20 and 21 to the combustion chamber. This tends to keep the entire surface of the plate-tuyère structures that is exposed to the fuel in such cool condition as to minimize the tendency to clinker adhesion, but should in

tensity of the fire burn away any flange portion of the plates, the body-webs will afford a grid that will prevent the fire from falling through into the windbox below to any seriously detrimental extent.

It will be understood that specific changes in design may be made without departure from the spirit of my invention within the scope of the appended claims.

10 I claim:

1. A plate tuyère structure of the character described comprising a body web of substantially uniform thinness, having a rear vertical portion for contact with the furnace side wall, a bottom portion notched for engagement with the margin of a retort which is spaced from the side wall, a front edge and a top edge that together extend upwardly and rearwardly affording a relatively long span between the bottom of the structure and the top of its rear edge, and a shallow marginal flange integral with said body web extending along the wall-contacting portion of the rear edge and along the top and front edges, said flange extending from one side only of the plate and being laterally interrupted, near its bottom to

afford tuyère-openings, the portions 22 between said openings extending further back from the front edge of the plate than the general depth of the remainder of the bordering flange, substantially as and for the purposes described.

2. A side-tuyère structure of the character described, comprising a body web of substantially uniform thickness having a rear vertical portion for contact with the furnace side wall, a bottom portion having a notch near the front edge for engagement with the margin of a retort which is spaced from the side wall, a front edge, a top edge which slopes upwardly and rearwardly at an angle greater than the angle of repose of the material that will bear thereon, said front and top edges together affording a relatively long span between the bottom-notch and the top of said rear vertical portion, and a shallow marginal flange integral with said body web extending along the wall-contacting portion of the rear edge and along the top and front edges, the said top edge being so arranged as to fit laterally against a similar block to form a substantially plane surface.
